UNITED STATES PATENT OFFICE.

BENJAMIN WOLHAUPTER, OF CHICAGO, ILLINOIS.

COMBINED RAIL JOINT AND BOND.

SPECIFICATION forming part of Letters Patent No. 794,441, dated July 11, 1905.

Application filed November 28, 1904. Serial No. 234,637.

To all whom it may concern:

Be it known that I, BENJAMIN WOLHAUPTER, a citizen of the United States, and a resident of Chicago, in the county of Cook and State 5 of Illinois, have invented certain new and useful Improvements in a Combined Rail Joint and Bond; and I do hereby declare that the following is a full, clear, and exact description thereof, reference being had to the accompanying drawings, and to the letters of reference marked thereon, which form a part of this specification.

This invention relates to a combined rail-joint and rail-bond; and its object is to provide a construction in the connecting means for the ends of railway-rails by which a rail-bond or electric connector for the ends of the rails shall be embraced in or covered or enclosed by the parts constituting the rail-joint. 20 The invention consists in the matters hereinafter set forth, and more particularly pointed out in the appended claims.

A combined rail-joint and rail-bond embodying my invention embraces a base-plate 25 constituting part of the rail-joint and which extends beneath and forms a support or bearing for the adjacent ends of the rails. Said plate has in its upper or bearing surface, which forms the rail-seat, a longitudinal groove or 30 recess, and an electric conductor is located within said groove or recess beneath the ends of the rails and having permanent contact with the latter. The electric conductor thus located in said groove or recess is thus enclosed within a space or passage formed by said groove or recess and the ends of the rails above it, and is thereby protected from injury or external violence.

My invention, embracing the general features of construction above set forth, may be carried out in several different ways in practice, and I have illustrated in the accompanying drawings several different forms of rail-joint embodying the invention.

In one desirable form of construction embodying my invention the rail-bond consists of a strip of metal made thick enough to fill the vertical space between the rails and the bottom of the groove or channel in the base- 50 plate and to rest or bear upwardly against the

lower surfaces of the rails, the same being clamped firmly in contact with the rails by the members of the rail-joint, while the downward pressure of the ends of the rails on said metallic strip serves to insure always an intimate 55 contact of the strip with the rails. In another embodiment of my invention illustrated in the accompanying drawings the conducting-strip so located within a groove in the base-plate is pressed upwardly against the rails by a 60 spring. In still another embodiment of my invention illustrated in the accompanying drawings the ends of a conducting-strip located in the longitudinal groove in the base-plate are extended upwardly through holes in 65 and riveted to the base-flanges of the rails.

As illustrated in said drawings, Figure 1 is a perspective view of a rail-joint embodying a form of my invention in which the rail-bond consists of a strip of metal inserted in 70 the longitudinal groove in the base-plate of the rail-joint and bearing against the under surface of the rail ends. Fig. 2 is a view in cross-section of the rail-joint. Fig. 3 is a plan view of the base-plate of the rail-joint. 75 Fig. 4 is a sectional view of a rail-joint having two joint bars or plates only. Fig. 5 is a section like Fig. 3, showing a slightly-modified construction of the base-plate. Fig. 6 is another section like Fig. 3, showing still an- 80 other modification in the construction of the base-plate. Fig. 7 is a section corresponding with Fig. 3, illustrating a construction in which the conducting-strip is held by a spring upwardly against the bottom surfaces of the 85 rails. Fig. 8 is another section corresponding with Fig. 3, showing the conducting-strip so arranged as to itself constitute a spring. Fig. 9 is a cross-sectional view of a rail-joint having a conducting-strip which is permanently 90 secured at its ends to the base-flanges of the rail. Fig. 10 is a sectional view of the same, taken on line 10-10 of Fig. 9. Fig. 11 is a plan view of the base-plate with a conducting-strip like that of Figs. 9 and 10 located in the 95 groove thereof.

In all of the figures of the drawings except Fig. 4, A A indicate the ends of the rails to be joined, B the base-plate of the rail-joint, and C angle-plates, which coact with the 100

base-plate to form said rail-joint and which are clamped against opposite sides of the rails by means of the track-bolts D D.

The base-plate B and angle-plates C C are joined or connected in such manner that the said base-plate will be clamped or held firmly in contact with the bottom surface of the rail. Such clamping action may be obtained by any one of a number of different devices, such as 10 to have heretofore been used in rail-joints. A desirable form of construction for this purpose is shown in the accompanying drawings, which is like that described and claimed in Letters Patent of the United States No. 15 691,087, granted to me January 14, 1902. In this construction the angle-plates C C are provided at their lower or outer margins with inwardly-directed flanges C' C', which extend beneath and engage the adjacent marginal 20 parts of the base-plate B. Said angle-plates have downwardly-facing oblique bearing-surfaces c c, that bear upon the inclined upper surfaces of the base-flanges of the rail, these parts being so arranged that as the angle- 25 plates are drawn inwardly toward the web of the rail by the track-bolts D D the oblique surfaces C C will slide upwardly and inwardly on the base-flanges, and thus draw or clamp the base-plate B, which is engaged with the 30 flanges C' C', firmly into contact with the lower surfaces of the rail ends. If desired, the meeting or contact surfaces of the flanges C' C' and the margins of the base-plate B may be inclined or beveled upwardly and outwardly, 35 as shown in the drawings, in order to increase the clamping action referred to.

The base-plate B is provided in its upper surface with two or more longitudinal grooves B' B', which grooves may be formed by giving 40 corrugated shape to the plates as a whole.

Now referring to the construction illustrated in Figs. 1 to 3, inclusive, E E indicate bonding or connecting strips, which are of 45 rectangular form in cross-section and which rest within the grooves B' B' in position for contact of their upper surfaces with the ends of both rails A A. Said bonding-strips E E will preferably be made originally slightly greater in vertical thickness than the depth 50 of the grooves B' B', the result of this construction being that not only will said strips be firmly clamped against the rails when the angle-plates C C are clamped against the rails in assembling the parts of the joint, but the 55 rails will rest upon and be supported by said bonding-strips and the load coming on the rails will tend to press the same against the strips, and thus maintain reliable contact of the strips with the rails. The said bonding- 60 strips will, however, usually be made of copper or other metal softer than that used for the parts of the joint, and when said strips are originally made somewhat thicker than the depths of the grooves said strips may and 65 generally will be somewhat compressed or

flattened by pressure of the rails thereon under passing loads, and the upper surface of the strips will be made to conform to minute irregularities in the bottom surface of the rails, thereby insuring close or intimate contact of the strips with the rails. 70

As shown in Fig. 4, C² C² indicate angle-plates which are provided at their lower edges with inwardly-extending horizontal parts C³ C³, which extend beneath the rails and, on 75 which the rails rest. Said parts C³ C³ in this construction take the place of the base-plate B of the other figures of the drawings, the said parts C³ C³ being provided with grooves C⁴ C⁴, in which are located bonding-strips E 80 E, arranged and operating like those of Figs. 1, 2, and 3.

In the construction illustrated in Fig. 5 the base-plate B has cut from the bottom walls of the grooves B' B' therein longitudinal inwardly-directed tongues b b, which tongues are bent upwardly into the grooves, as shown, so as to constitute shoulders located in contact with or adjacent to the ends of the bonding-strips E. The shoulders so formed in 90 the bottoms of said grooves of the base-plate serve to hold the bonding-strips in place at the time of originally assembling the parts and to also avoid possibility of said strips slipping out of place through endwise movement which might be given thereto through contraction and expansion of the rails. 95

Figs. 6, 7, and 8 illustrate a construction embracing a bonding-strip E', which instead of resting on the bottom walls of the grooves 100 in the base-plate is pressed upwardly against the bottoms of the rails by means of a spring suitably applied for the purpose. As shown in Fig. 6, said spring is formed by means of tongues cut from the bottom of the plate 105 itself. Said tongues, as indicated by b' b' in Fig. 6, extend longitudinally of the base-plate, with their free ends directed outwardly from the center thereof, and are bent or deflected upwardly from the central part of the 110 base-plate, so that their ends will form yielding or spring supports for the bonding-strip E', which in this instance is made of less depth or vertical thickness than the depth of the recess in which it is placed. As shown in 115 said Fig. 5, the end portions of the tongues b' b' are bent abruptly upward, so as to constitute shoulders serving to hold the bonding-strip from endwise movement and to properly confine in place said bonding-strip. 120

As shown in Fig. 7, the base-plate B is made in the same manner as illustrated in Fig. 5—that is to say, it is provided with upturned tongues b b, constituting shoulders adapted to hold the bonding-strip from endwise movement, while said bonding-strip is made of less thickness than the depth of the 125 grooves, and a flat or curved plate-spring E' is interposed between the central part of the base-plate and the said bonding-strip. Said 130

spring F will be made of considerable rigidity, so that the ends of the bonding-strip will be pressed firmly thereby against the lower surface of the rail ends.

5 As shown in Fig. 8, a bonding-strip G is used which has formed integral therewith free-ended spring-arms g g, that are deflected downwardly and are adapted to constitute springs which bear against the bottom of the 10 groove in the plate and serve to press the bonding-strip upwardly against the ends of the rails. In this construction shoulders to hold the bonding-strip centrally in position beneath the rail ends are afforded by means 15 of upwardly-deflected parts b b, bent from the metal of the base-plate after the same has been given its grooved or corrugated form.

Figs. 9, 10, and 11 illustrate a construction in which a bonding or connecting strip is 20 used having at or near its ends integral studs or pins which extend through holes in the base-flanges of the rails and are secured therein by riveting or upsetting the upper ends of said pins or studs. In this instance, H indicates the bonding-strip, which is located in 25 and extends longitudinally of the groove B' and which has at its ends upwardly-extending pins h, which are inserted in sockets or holes a a in the base-flanges of the rails and 30 the upper ends of which are upset or riveted against the said base-flanges. I prefer to make the bonds or connecting-strip H with enlarged or thickened parts or heads H' H', from the upper surface of which pins h h project and 35 which are made equal in vertical thickness to or somewhat thicker than the depth of the grooves B' in which they are placed, so that said heads H' will rest on the bottom of the grooves and the bottom of the rails will rest or bear upon the top surfaces of said heads. Moreover, I prefer to make the said pins h h of tapering form, the result of this construction being that the weight coming on the rails 50 will not only force the conical pins h h farther into their sockets, but the bottoms of the rails will rest on the heads H', and thus insure the maintenance of a tight joint or connection between the rails and the ends of the conducting-strip if there should be any defect in the 55 joints formed by the riveting of said pins in the rail-flanges.

In the several forms of devices illustrated in Figs. 1 to 8, inclusive, the ends of the rails in the expansion and contraction of said rails 55 by heat and cold will be permitted to move relatively to the bonding-strip by sliding or slipping thereon while being held in close contact with the rails either by the clamping action of the parts of the joints or by the spring 60 applied for the purpose; but in the construction shown in Figs. 9, 10, and 11 inasmuch as the ends of the bonding-strip are secured to

the rail-flanges it is necessary to provide for such relative endwise movement of the ends of the strips under expansion and contraction 65 of the rails. For this purpose the said strip H is made thinner and narrower than the width of the groove in the base-plate B and is bent into zigzag or curved form as to be capable of endwise expansion or contraction, and thus 70 permit its ends to be shifted or moved toward and from each other as the rails expand and contract.

Inasmuch as the part of the joint on which the ends of the rails rest and in which the 75 groove containing the bonding or connecting strip is formed may be made either as a part separate from the angle-plates applied to the sides of the ribs or may consist of inwardly-extending flanges on said angle-plates, as 80 shown in Fig. 4, it is to be understood that the term "base-plate" as used in the appended claims is not limited to a plate made in one piece or a plate made separate from the angle-plates, but is intended to cover any part 85 or parts of the joint extending beneath the rails and constituting a supporting means therefor.

I claim as my invention—

1. A rail-joint comprising a base-plate on 90 which the ends of the rail rest and which is provided with a longitudinal groove in its top surface, and a bonding or connecting strip located in said groove in contact with the bottom surfaces of the rail ends, said rail-joint 95 embracing means by which the said base-plate is clamped toward the bottoms of the rail ends and said bonding or connecting strip thereby pressed firmly against the same.

2. A rail-joint embracing a base-plate on 100 which the ends of the rails rest and which is provided with a longitudinal groove in its top surface, and a bonding or connecting strip in said groove, the base-plate having in the bottom of the groove elevated parts adapted to 105 hold the bonding-strip from endwise movement.

3. A rail-joint embracing a base-plate on 110 which the ends of the rails rest and which is provided with a longitudinal groove in its top surface, and a bonding or connecting strip in said groove, the base-plate having in the bottom of said groove tongues which are bent upwardly to constitute stops to hold the strip from endwise movement.

115 In testimony that I claim the foregoing as my invention I affix my signature, in presence of two witnesses, this 25th day of November, A. D. 1904.

BENJAMIN WOLHAUPTER.
